US00D937254S

(12) **United States Design Patent** (10) **Patent No.:** **US D937,254 S**
Chen et al. (45) **Date of Patent:** **** Nov. 30, 2021**

(54) **NOTEBOOK COMPUTER**

- (71) Applicants: **Pai-Feng Chen**, Taipei (TW);
Jyh-Chyang Tzou, Taipei (TW);
Han-Tsai Liu, Taipei (TW)
- (72) Inventors: **Pai-Feng Chen**, Taipei (TW);
Jyh-Chyang Tzou, Taipei (TW);
Han-Tsai Liu, Taipei (TW)
- (73) Assignee: **COMPAL ELECTRONICS, INC.**,
Taipei (TW)

(**) Term: **15 Years**

(21) Appl. No.: **29/699,687**

(22) Filed: **Jul. 29, 2019**

(51) LOC (13) Cl. **14-02**
(52) U.S. Cl.

(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in an alternate state of use;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines illustrate portions of the notebook computer and form no part of the claimed design.

1 Claim, 12 Drawing Sheets
